UNITED STATES PATENT OFFICE

107,791

DESIGN FOR AN ELECTRIC FAN GUARD

Lorenz Duane Petee, Crestline, Ohio, assignor
to Dominion Electrical Manufacturing Com-
pany, a corporation of Ohio

Application July 26, 1937, Serial No. 70,666

Term of patent 7 years

To all whom it may concern:

Be it known that I, Lorenz Duane Petee, a citizen of the United States, residing at 121 Railroad Avenue, in the city of Crestline, county of Richland, and State of Ohio, have invented a new, original, and ornamental Design for an Electric Fan Guard, of which the following is a specification, reference being had to the accompanying drawing, constituting a part thereof.

Figure 1 is a front elevational view of an electric fan guard showing my new design.

Figure 2 is a side elevational view of the electric fan guard shown in Figure 1.

I claim:

The ornamental design for an electric fan guard, substantially as shown.

LORENZ DUANE PETEE.
